UNITED STATES PATENT OFFICE.

PAUL J. STUPARICH, OF SAN FRANCISCO, CALIFORNIA.

DESIGN FOR A PHOTOGRAPHIC CARD-MOUNT.

SPECIFICATION forming part of Design No. 26,427, dated December 22, 1896.

Application filed November 19, 1896. Serial No. 612,768. Term of patent 3½ years.

To all whom it may concern:

Be it known that I, PAUL J. STUPARICH, a citizen of the United States, residing in the city and county of San Francisco, State of California, have invented a certain new and useful Design for Photographic Card-Mounts, of which the following is a specification.

My design is fully illustrated in the accompanying drawings, in which—

10 Figure 1 is a face view of a card, illustrating the design. Fig. 2 is a detail view of one of the angle ornaments.

15 The card may be rectangular, of any desired proportions, having a central smooth medallion A for the reception of the picture.

Surrounding the medallion is a roughened surface B, and in the angles exterior to the medallion I have printed the special features of my design.

20 My design consists of embossed oval figures C, surrounding a central oval space D, the surface of which is formed of transverse corrugations or bars. Centrally within this oval is imprinted a raised or embossed fleur-de-lis E. Exterior to the oval in the line of

its longest diameter is imprinted an embossed crown F. Upon the inner side, below the oval, near to the central medallion of the card, is a raised ring or loop G, having extending outwardly from it leaves or branches 30 H, and between these branches and the sides of the oval are other branches having flowers represented upon them, the whole being embossed and raised above the roughened surface of the card.

35 The essential feature of my design is the embossed oval with the crown and branches imprinted upon the roughened surface in the angles of the card and exterior to a central medallion.

40 I claim—

The design for a photographic card-mount, substantially as shown and described.

In witness whereof I have hereunto set my hand.

PAUL J. STUPARICH.
